Primary Examiner — Clare Ann Gannon(57) **CLAIM**

The ornamental design for electric skylight blinds, as shown and described.

DESCRIPTION

FIG. 1 is a perspective view of electric skylight blinds, showing our new design;
 FIG. 2 is a front view thereof;
 FIG. 3 is a rear view thereof;
 FIG. 4 is a left view thereof;
 FIG. 5 is a right view thereof;
 FIG. 6 is a top view thereof;
 FIG. 7 is a bottom view thereof; and,
 FIG. 8 is a perspective view thereof in a position of use. The dashed or broken lines shown in the drawings depict portions of the electric skylight blinds in which the design is embodied that form no part of the claimed design.
